UNITED STATES PATENT OFFICE

ROBERT CHELTON, OF CHICAGO, AND CHARLES R. KEERAN, OF EVANSTON, ILLINOIS,
ASSIGNORS, BY MESNE ASSIGNMENTS, TO SWANBERG MANUFACTURING COMPANY,
OF CHICAGO, ILLINOIS, A CORPORATION OF ILLINOIS

MECHANICAL PENCIL

Application filed February 14, 1927. Serial No. 167,923.

This invention relates to mechanical pencils and its object is to provide a construction which shall be economical to manufacture and simple to repair, and which is adapted to utilize a somewhat longer lead than most constructions now in commercial use. The invention consists in certain features and elements in combination, as herein shown and described and as indicated by the claims.

10 In the drawings:

Figure 1 is an axial section of a pencil embodying this invention.

Figure 2 is a partial axial section of the same on a larger scale.

15 Figure 3 is a transverse section taken as indicated at line, 3—3, on Figure 1.

Figure 4 is a transverse section taken as indicated at line, 4—4 on Figure 1.

20 Figure 5 is a detail view of the lead-propelling plunger.

Figure 6 is a detail view of the plunger taken at right angles to the view of Figure 5.

Figure 7 is an end view of the plunger.

25 Figure 8 is an axial section of a modified form of the pencil.

Figure 9 is a transverse section taken as indicated at line, 9—9, on Figure 8.

As shown in Figure 1 the structure includes a barrel, 1, which is preferably ornamental in 30 character and may be composed of celluloid, of bakelite, hard rubber or other composition, and which is fitted at its upper end with a tubular metallic ferrule, 2, reduced to receive a cap, 3, which encloses an eraser rubber, 4, and its holder, 5. Said holder, 5, serves as a closure for the upper end portion of the barrel which may be used as a container for 35 spare leads indicated at 6. Preferably a lining tube, 7, is inserted in this upper end portion to form a shoulder against which a partition member, 8, is entered from the opposite end of the barrel, 1.

The lead-propelling mechanism is operated by rotation of the tapered tip member, 9, 40 which may be split at 9^a, for a short distance back from its smaller end to furnish frictional guidance for the lead, 10, in use. A filler, 11, secured near the smaller end of the tip, 9, is formed with a bore substantially fitting the lead, 10, and in the upper end of

said filler there is anchored the propelling screw which is in the form of an open spiral, 12, constructed from a flat metal ribbon helically coiled with spaces, 12^a, between adjacent coils. A plunger, 13, is loosely slideable in the 45 helical coil, 12, and is provided with laterally projecting lugs or wings, 13^a, which extend radially through the spaces, 12^a, and project beyond the outer diameter of the coil, 12. The projecting ends of the lugs, 13^a, are engaged in longitudinal guide grooves of a stationary guide tube, 14, and said grooves are 50 preferably formed by making the tube, 14, of corrugated cross-section with corrugations diametrically disposed, as indicated in Figure 3. If desired this may be accomplished by a swaging or rolling process applied to a tube of initially circular cross section and preferably the tube is formed with 55 four corrugations disposed in pairs at right angles to each other so that its external form may be circumscribed by a square and the tube, 14, will be held against rotation when inserted into such circumscribed square. The 60 lower end of the guide tube, 14, is permanently secured in a bushing, 15, tapered at one end to conform to the taper of the outer tip, 9, and having a cylindrical portion, 15^a, which abuts against the end of the barrel, 1, with a reduced portion, 15^b, which is inserted 65 snugly into the bore of the barrel, 1, as seen in Figures 1 and 2. The inner diameter of the part, 15^b, and the inner diameter of the tapered end portion at its extreme end are 70 substantially equal to that of the circle which will just circumscribe the corrugated guide tube, 14, so that the tube is snugly centered in the bushing, 15, and may be permanently fixed therein by the application of a small amount of solder in the bore of the reduced 75 part, 15^b. The bushing, 15, is flanged over at its smaller end as seen at 15^c, forming a stop against which the corrugated tube, 14, is inserted. This assembly of the corrugated tube, 14, and the bushing, 15, thus constitutes 80 a guide unit upon which the tip, 9, is rotatably mounted and which is itself fixed to the barrel, 1, by frictional engagement of the part, 15^b, in the bore of the barrel. Preferably this engagement is rendered more posi- 85

90

100

tive by making a partition member, 8, in the form of a cup with side walls, 8^a, swaged to circumscribe the square form of the guide tube, 14, so as to hold it against rotation as indicated in Figure 4,—the partition, 8, being a comparatively tight fit in the barrel, 1, and being forced to its position therein.

When the parts are thus assembled, it will be seen that the plunger, 13, while freely 10 slideable in axial direction, will be held against rotation by engagement of its lugs, 13^a, in the grooves of the corrugated tube, 14, but that rotation of the tip, 9, on the bushing, 15, will turn the coil, 12, so as to cause the helical 15 groove formed by the space, 12^a, to feed the lugs, 13^a, up or down for advancing or retracting the lead-propelling plunger, 13.

The plunger, 13, is conveniently made from flat sheet stock initially blanked out with the 20 lugs, 13^a, projecting from its stem portion. In a second operation a forming die will give a stem a substantially circular cross section and produce beveled surfaces, 13^b, on the lugs, 13^a, which are inclined to correspond with 25 the pitch of the helical coil, 12, thus providing substantial surfaces for engagement with the coil to insure long wear and easy operation.

For still greater economy of manufacture 30 the bushing member, 15, may be dispensed with, as indicated in Figures 8 and 9. In this arrangement the barrel, 20, has a tapered terminal portion, 20^a, fitting into the tapered tip, 9, and within this portion a reduced bore 35 is formed to substantially fit the outer diameter of the coil, 12. From the shoulder, 20^b, which results from the reduced bore, the larger bore of the barrel, 20, is squared at 20^c, for a short distance for non-rotative engagement 40 with the corrugated guide tube, 14, which in this instance is inserted into the barrel from the upper end. A partition may be formed by closing over the end of the tube, 14 at 14^b, thus dispensing with any 45 separate member for this purpose. At its lower end portion the helical coil, 12, is wound at a different pitch so as to leave no space between its adjacent coils, and thus forms a substantially closed tube which is anchored 50 directly in the tip, 9, and centered therein by a bushing, 21. The plunger, 13, is of the same construction as already described and the structure at the upper end including the eraser, 4, and cap, 3, may be exactly like that 55 shown in Figure 1.

We claim:—

1. In a mechanical pencil, a barrel, a bushing inserted in the bore of the barrel at one end, a guide tube fixed in the bushing and 60 extending into the barrel, with means holding the tube against rotation in the barrel, a tapered tip having a bore for a pencil lead at its smaller end and supporting one end of an openly coiled helix whose opposite end is 65 open and extends into the guide tube, to-

gether with a plunger in the coil having laterally extending lugs projecting through the spaces of the coil for longitudinal sliding engagement with the guide tube, said lugs being disengageable from the helix through 70 its open end and means at the lower end of the guide tube for retaining the plunger by engagement with said lugs.

2. In a mechanical pencil, a barrel and a guide tube therein, a lead-propelling plunger 75 slideable longitudinally in the guide tube and holding means comprising a cup fitted tightly into the barrel, the cup being non-circular in cross section, and the guide tube having a non-circular cross section interlocked therewith.

3. In a mechanical pencil, a barrel, a bushing having a reduced end portion inserted in the bore of the barrel, said bushing being formed of relatively thin stock tapered toward its opposite end, a guide tube which is corrugated in cross-section fitted in said bushing, the inner diameter of the tapered end of the bushing and the inner diameter of the reduced end of the bushing being substantially equal and circumscribing the corrugated tube, said tapered end of the bushing having an in-turned flange whose diameter is that of the inscribed circle of the corrugated tube, a helical coil rotatable in said tube and a plunger in said coil having lugs projecting laterally through the spaces between adjacent turns of the coil for engaging the longitudinal grooves of the corrugated tube, together with an outer tip member for the pencil rotatable on the bushing and operatively engaging the outer end of the coil for turning it, said tip having a lead guide and bore at its outer end.

4. In a mechanical pencil, a barrel, a lining tube extending within said barrel through a part of its length, a partition cup in the barrel at the inner end of said lining tube, a guide tube extending through the remainder of the barrel from said cup and protruding from the end of the barrel, a bushing in which the protruding end of said guide tube is secured, said bushing having a reduced portion inserted in the bore of the barrel, the opposite end of the bushing being tapered, a tapered shell fitted rotatably over said bushing and a helical coil fixed in the outer end of said shell and extending into the guide tube, together with a plunger slideable in said coil and having laterally projecting lugs extending through the spaces between the turns of the coil for engagement with longitudinal guideways in the guide tube.

5. In a mechanical pencil, a barrel, a lining tube extending therein through a part of its length, a partition in the form of a cup with its bottom wall abutting said lining tube, the side walls of the cup forming a chamber of non-circular cross section, and 130

5 a guide tube occupying the remainder of the barrel corrugated to provide longitudinal grooves internally for engagement with a lead-propelling plunger slideable longitudinally therein, said tube externally presenting a non-circular form which is locked against rotation by insertion in the cup-shaped partition.

10 6. In a mechanical pencil, a barrel, a guide tube which is corrugated in cross section to provide longitudinally extending guide channels opening inwardly and giving the tube a polygonal form externally; an openly coiled helix rotatably carried in said tube and centered therein by contact with the corrugations, and a plunger axially disposed in the helix with laterally projecting lugs extending through the spaces between the turns of the coil for engaging the channels of the 15 guide tube, said guide tube being anchored 20 in the barrel to hold it against rotation.

In testimony whereof, we have hereunto set our hands, this 12th day of January, 1927.

ROBERT CHELTON.
